APPARATUS FOR THE PRODUCTION OF
HEAT AND COLD

Harry A. Musham, Chicago, Ill.

Application March 31, 1936, Serial No. 71,988

4 Claims. (Cl. 62—136)

(Granted under the act of March 3, 1883, as
amended April 30, 1928; 370 O. G. 757)

This invention described herein may be manufactured and used by or for the Government for governmental purposes, without the payment to me of any royalty thereon.

5 This invention relates to an apparatus for mechanically producing heat and cold, more especially it is directed to a means for compressing and expanding a working substance for the purpose of transferring heat from one substance to 10 another at maximum thermal efficiency.

Another object of this invention is to provide 15 an apparatus for producing heat by means of which the working substance is compressed to a predetermined temperature and pressure, cooled at constant pressure and then expanded to its initial pressure thus giving to the working substance the capacity for transferring heat.

Another object of this invention is to provide 20 a mechanical apparatus wherein a compressor, an expander and heat and cold interchangers situated therebetween are combined so as to provide in a single unit, means for refrigeration, heating and for cooling confined spaces.

The instant invention comprises a compact unit 25 for the production of heat and cold wherein a charge of air after compression is discharged into a primary intake chamber mounted upon the upper end of the compressor and then transferred at constant pressure to a primary discharge chamber through a heat interchanger located between the chambers, the heat of compression being extracted from the charge during its passage through the heat interchanger, the extraction being effected by a current of air flowing 30 through the heat interchanger. The cooled air collecting in the primary discharge chamber is periodically injected into an expander underlying the discharge chamber. After expansion the charge is delivered to a secondary intake 35 chamber from which it is transferred at constant pressure to a secondary discharge chamber through a heat interchanger situated between the chambers immediately adjacent the first mentioned interchanger, the cold air passing 40 through the interchanger being employed to extract heat from the current of air flowing through the interchanger. The air collecting within the secondary discharge chamber is periodically returned to the compressor and the cycle just described repeated.

Referring more particularly to the accompanying drawings in which corresponding parts are indicated by similar reference characters:

Fig. 1 is a top plan view of the assembly, partly in section, illustrating its practical applica-

tion to heating and cooling the interior of a building and for cooking and refrigeration;

Fig. 2 is a vertical section partly in elevation taken on the line 2—2 of Fig. 1.

Coming now to the description of the apparatus 5 forming the subject matter of the instant application and referring to Figures 1 and 2 of the drawings, 1 indicates a foundation, 2 a prime-mover, 3 a compressor, 4 the heat interchanger and 5 the expander, all of which are suitably 10 mounted upon the foundation 1. Compressor 3 includes a crank case 6, cylinder 7 and a constant pressure chamber 8 surmounting the cylinder. Expander 5 consists of a crank case 6', a cylinder 7' and a constant pressure chamber 8' surmounting 15 the engine cylinder. Pistons 9 and 9' operating in cylinders 7 and 7' of the compressor and expander respectively, are connected to a common crank shaft 10, by connecting rods 11 and 11', the crank shaft 10 being operatively connected with the prime-mover 2 through a coupling 12.

Cylinder 7 of the compressor is formed adjacent its head with an intake port 13 controlled by a slide valve 14 having a port 15. Valve 14, 25 is operated by a cam 15 positioned on crank shaft 10 and adapted to be engaged by the lower end of a follower 16, the upper end of which is connected to slide valve 14. As the cam rotates the follower is lifted against the action of spring 17 to 30 reciprocate the valve as shown in Fig. 2 of the drawings. To permit the working substance after compression to pass from the compressor to the constant pressure chamber 8, the head of cylinder 7 is formed with a port 18' controlled by a 35 valve 16, which is operated by rocker arm 18, follower 19 and cam 20 positioned on crank shaft 10. The free end of rocker arm 18 engaging the upper end of the stem of valve 16 depresses the stem against the action of spring 21 and unseats 40 the valve, as clearly shown in Fig. 2 of the drawings.

The cylinder 7' of expander 5 is formed adjacent its head with the ports 17 and 18, which are controlled by slide valves 19 and 20, the former 45 having therein an opening 21, the latter an opening 22. Both of these valves may be controlled from the crank shaft or other moving parts by a suitable mechanism.

Pressure chamber 8' communicates with cylinder 7 through port 18' controlled by a valve 17' as clearly shown in Fig. 2 of the drawings. Valve 17' is operated by a rocker arm 22 and a follower 23, the latter having one end engaging said rocker arm and its opposite end contacting with cam 24 55

on crank shaft 10. The free end of rocker arm 82 engaging the stem of valve 17' depresses said stem against the action of spring 85 and unseats the valve. The constant pressure chambers 8 and 8' of compressor 3, and expander 5, through inflow and release conduits 23 and 23' are in communication with cook stove 24, the conduits being controlled by valves 25. Pressure chamber 8 is also provided with a spring pressed safety valve 26. The pressure chamber 8' is equipped with a pressure regulator consisting of sleeve 27, the lower end of which communicates with the interior of the cold chamber 8'. A piston 28 operates in sleeve 27 and is connected to a counterweighted arm 29. With this arrangement the pressure within the cold chamber may be regulated by shifting the counterweight to any desired position on the arm 29, as will be understood without further discussion.

20 The heat interchanger 4 which is situated between the constant pressure chambers 8 and 8' respectively, consists of a suitable casing 30 having therein horizontally disposed tubes 31, which serve to establish communication between the two chambers 8 and 8', as clearly shown in Fig. 2 of the drawings. Within the casing 30 there are arranged a series of baffle plates 32, so that air entering in the opening 33 in the bottom of the casing 30 will take a circuitous course over the tubes 31 to outlet 34, through which it is adapted to flow into the hot air dome 35, formed in the upper portion of the casing 30. Air dome 35 communicates with distributing conduits 36 and 37, through leads 38 and 39 controlled by valves 35 38' and 39'. Opening 33 in the bottom of the heat interchanger 4 is connected with a suitable blower 40. The air from the blower passes over the tubes in a direction opposite to the flow of the working substance through the tubes, thus impeding the air entering the air dome 35, a temperature approximating the compression temperature of the compressed working substance in the hot pressure chamber 8'. The tubes in the interchanger 4 are slightly tapered from the ends 40 communicating with the hot pressure chamber 8 to those opening into the cold pressure chamber 8'. This construction has been found to facilitate the maintenance of constant pressure during the heat extraction period.

50 Adjacent to the pressure chamber 8 on the upper end of the compressor 3 is a cold air compartment 41, the interior of which communicates through conduit 42 and port 15 of slide valve 14 with the intake port 13 of compressor 3. Likewise adjacent the cold pressure chamber 8' of the expander 5 is another cold chamber 43. Between chambers 41 and 43 there is arranged an interchanger 4' corresponding in detail to the interchanger 4, that is to say, it consists of a casing 44 having an air dome 44' in its upper portion, a series of horizontally disposed transfer tubes 46 passing through the central portion of the casing and communicating at their respective extremities with chambers 41 and 43. This interchanger, like that previously described, is also provided with a series of baffle plates positioned to form a circuitous path over the transfer tubes 46 whereby air entering the casing through a suitable opening in its bottom, after passing over the tubes in the direction opposite the flow of the working substance, enters the air dome 44' in the upper portion of the casing 44 from which it is conducted through conduits 45 or 47 to distributing leads 36 or 37, as clearly shown in Figure 1 75 of the drawings. A fan, (not shown) mounted

on the shaft of blower 40 functions to direct air through the passage 46 leading from the blower to the opening in the bottom of the casing 44 and through the latter to the transfer tubes as hereinabove stated. Chamber 43 communicates with cylinder 7' of expander 5 via conduit 48 and port 21 in slide valve 19. Slide valve 19 is operated by a cam follower 86, one end of which is attached to the slide valve. The other end of follower 86 engages cam 87 on crank shaft 10, so that rotation of the cam lifts follower 86 against the action of the spring 88 and reciprocates the valve as shown in Fig. 2 of the drawings.

A part of the working substance after expansion may be taken from the top of expander 5 for refrigerating purposes, and to accomplish this end exhaust port 18 of cylinder 7' is connected with a refrigerator 56, via port 22 of slide valve 20 and pipes 57 and 58 communicating with the interior of the refrigerator. The cold air after circulation through the refrigerator is conducted to the outside via conduits 59 and 60. Slide valve 20 is controlled by a cam follower 89, one end of which is attached to the valve. The other end of follower 89 engages cam 90 on crank shaft 10, so that rotation of the cam lifts follower 89 against the action of spring 91 and reciprocates the valve, as clearly shown in Fig. 1 of the drawings.

A hot water coil 54 may be placed within the constant pressure chamber 8 for the purpose of heating a supply of water for reservoir 55, as shown in Fig. 2 of the drawings. In this connection it is to be understood that such auxiliaries as the hot water coil, the stove and the refrigerator, form no part of the instant invention and are disclosed merely to illustrate the various usages to which the instant apparatus may be placed.

Under some conditions it may be desirable to dissipate the air collecting in air domes 35 and 44 of the interchangers 4 and 4' and to accomplish this conduits 39 and 47 are provided to establish communication between said air domes and the exhaust pipe 37, as clearly shown in Figs. 1 and 2 of the drawings. Normally the valves of conduits 39 and 47 respectively, are closed. When occasion demands these valves may be opened and the air thus allowed to pass to the pipe 37. In order to enable the system to be charged with further air whenever desirable, the cold pressure chamber 41 is equipped with a manually controlled air inlet 62, the valve of which is normally maintained in closed position.

Having described the structural details of one embodiment of this invention, its operation will be seen to be as follows:

A charge of the working substance is compressed to the desired temperature and pressure by the compressor 3. At the point of maximum compression this charge is admitted (by a valve 16) to the constant pressure chamber 8 from which it is transferred at constant pressure through the tubes 31 of the interchanger 4 to the chamber 8'.

Meanwhile, a blast of air, produced by blower 40 passes circuitously over the tubes of the interchanger, abstracts their heat and enters dome 35 from which it is distributed via conduits 38 and 36 to the space to be heated.

When the piston 9' of expander 5 reaches the top of its stroke, valve 17' opens and the working substance having lost in chamber 8', the greater portion of its heat at constant pressure, is permitted to enter cylinder 7' of the expander 5, wherein it is expanded and then exhausted

through conduit 48 to cold chamber 43. From chamber 43 the working substance passes at constant pressure through the tubes 48 of interchanger 4' to cold chamber 41, and thence 5 through conduit 42 to compressor 3. During the transfer of the expanded working substance from chamber 43 to chamber 41 a blast of air passing over the tubes in a circuitous path is lowered in temperature and collects in dome 44' from which 10 it may be distributed to pipe 38 via conduit 45.

In conclusion it will be seen this invention provides a comparatively inexpensive apparatus for effecting maximum recovery of the energy expanded in the treatment of the working substance, the limit of expansion in each stage being determined by the critical temperature of the working substance.

Although in the foregoing certain elements have been described as best adapted to perform 20 the functions allotted to them, nevertheless it is to be understood that various minor changes, such as operating the apparatus on an open instead of a closed heat cycle, may be resorted to within the scope of the appended claims without 25 departing from or sacrificing any of the principles of this invention.

Having described my invention, what I claim as new and wish to secure by Letters Patent is:

1. An apparatus for effecting a transfer of heat 30 from one substance to another including in combination a compressor, and an expander arranged in juxtaposition, each including vertically disposed cylinders, an intake pressure chamber disposed upon the upper end of the compression 35 cylinder, valve controlled means for introducing the charge of the compressor at maximum compression directly into the intake pressure chamber, a discharge pressure chamber situated upon the upper end of the expander cylinder, pressure 40 regulating means in connection with the respective chambers, a series of heat transfer elements interconnecting said chambers, valve-controlled means for periodically exhausting a portion of the contents of the discharge chamber directly into said expander, means for transferring 45 the contents of the expander to the compressor and means directing a current of air over said transfer elements to abstract the heat of compression and additional means for collecting and distributing the air passing over said elements.

2. An apparatus for effecting the transfer of heat from one substance to another, comprising 50 in combination a compressor and an expander arranged in juxtaposition, each including a vertically disposed cylinder, an intake pressure chamber situated upon the upper end of the compressor cylinder, valve controlled means for introducing the contents of the compressor at maximum compression directly into the intake 55 pressure chamber, a discharge pressure chamber situated upon the upper end of the expander cylinder, pressure regulating means in connection with the respective chambers, a heat interchanger situated between and interconnecting the intake and discharge chambers, said interchanger including a series of horizontally disposed heat transfer elements communicating at their extremities with said chambers, a casing 60 inclosing the heat transfer elements and having an air collecting dome, blast producing means in communication with said casing, additional means within said casing for directing the blast of air in a circuitous path over the heat transfer elements and into said collecting dome, valve-controlled means for periodically discharging a portion of the contents of the discharge chamber 65 into said expander and means for returning the expanded air from the expander to the compressor, said means including auxiliary intake and discharge pressure chambers, and an auxiliary heat interchanger situated between and interconnecting the chambers, the auxiliary interchanger and pressure chambers being disposed immediately adjacent the first mentioned chambers and interchanger.

means within said casing for directing a blast of air in a circuitous path over the heat transfer elements and into said collecting dome, valve-controlled means for periodically discharging a portion of the contents of the discharge chamber into said expander and means for returning the expanded air from the expander to the compressor.

3. An apparatus for effecting a transfer of heat from one substance to another comprising 10 in combination a pressure and an expander arranged in juxtaposition, an intake pressure chamber situated upon the upper end of the compressor cylinder, valve-controlled means for introducing the contents of the compressor at maximum compression directly into the intake pressure chamber, a discharge pressure chamber positioned upon the upper end of the expander cylinder, pressure regulating means in connection with the respective chambers, a heat interchanger 20 situated between and interconnecting the intake and discharge chambers, said interchanger including a series of horizontally disposed heat transfer elements communicating at their extremities with said chamber and a casing enclosing said heat transfer elements, blast producing means communicating with the casing, means within the casing to direct the blast of air over the transfer elements and into the collecting dome, means for periodically discharging a portion of the contents of the discharge pressure chamber into said expander, and means for returning the expanded air from the expander to the compressor.

4. An apparatus for effecting a transfer of heat from one substance to another, comprising 30 in combination a compressor and an expander arranged in juxtaposition, an intake pressure chamber situated upon the upper end of the pressure cylinder, valve controlled means for introducing the contents of the compressor at maximum compression directly into the compression chamber, a discharge-pressure chamber mounted on the upper end of the expander, pressure regulating means in connection with the respective chambers, a heat interchanger situated between and interconnecting the intake and discharge chambers and including a series of horizontally disposed heat transfer elements communicating at their extremities with said chambers, a casing inclosing the heat transfer elements and having an air collecting dome, said dome being provided with valve-controlled distributing outlets, blast producing means in communication with said casing, additional means 50 within said casing for directing the blast of air in a circuitous path over the heat transfer elements and into said collecting dome, valve-controlled means for periodically discharging a portion of the contents of the discharge chamber 55 into said expander and means for returning the expanded air from the expander to the compressor, said means including auxiliary intake and discharge pressure chambers, and an auxiliary heat interchanger situated between and interconnecting the chambers, the auxiliary interchanger and pressure chambers being disposed immediately adjacent the first mentioned chambers and interchanger.
